UNITED STATES PATENT OFFICE.

ALBERT F. BEMIS, OF NEWTON, MASSACHUSETTS, ASSIGNOR TO BEMIS INDUSTRIES INC., OF BOSTON, MASSACHUSETTS, A CORPORATION OF DELAWARE.

BUILDING UNIT.

Application filed December 2, 1925. Serial No. 72,675.

In my copending application, Serial No. 33,173, filed September 12, 1925 I have described one manner in which standardized units may be combined to form a primary outline of a building, while in applications Nos. 72,673, 72,674 and 72,678, filed of even date herewith, I have shown other ways of fabricating primary outlines for buildings out of standardized units. The novel units disclosed in the present application may be combined in the various manners described in the above identified applications.

This invention relates more particularly to the provision of standardized building units which may be pre-formed in a manufacturing establishment and rapidly assembled in situ with the minimum of time and labor required for actual erection. These units may be combined to form the basis for any of the walls of a building such as side walls or partitions, floors, flat or pitched roofs or the like. A wide variety of materials may be used in the manufacture of such units, for example metal, wood, or other fibrous material such as fiber board, cementitious material such as gypsum or Portland cement, fibrous or granular substances combined with a binder of cementitious material such as straw-board, chip-board, fiber board, or the combination of sand, cinders, or ashes, etc. with a cementitious substance, or other combinations of these and other suitable materials may be used for the formation of the units described in this application.

The specific embodiments of my invention shown herein are more particularly distinguished by the provision of a flat outer face which may be aligned with similar faces of adjoining units either to form the finish of a wall, ceiling, floor, or roof of a building or to form the backing for the application of an outer finish such as stucco, plaster, wall-board, clapboards or the like. The utilization of tubular units with flat outer faces designed to be aligned with similar faces of adjoining units not only has the advantage of enabling a quick assembly of the units, as explained in the applications identified above, but also of permitting the formation of a finishing surface, or a continuous surface for application of finishing material, at the same time and with no greater effort. Thus in accordance with the present embodiment of my invention, units may be rapidly assembled and aligned in practically one op-

eration, not only to form the primary outline of a building, but also to provide either the finished surface therefor or a continuous surface ready for the immediate application of finishing materials.

Many other advantages of my invention will appear to those familiar with the art from a reading of the following description in conjunction with the drawings in which:

Fig. 1 is a perspective view of a structural unit;

Fig. 2 is a perspective view of a portion of a floor;

Fig. 3 is a perspective view of another form of unit;

Fig. 4 is a similar view of a different unit;

Fig. 5 is a similar view of a slightly different unit;

Fig. 6 is a perspective view of a wall formed of units such as shown in Fig. 5;

Figs. 7, 8, 9 and 10 are each perspective views of structural units;

Fig. 11 is a perspective view of another type of wall;

Fig. 12 is a detail view;

Fig. 13 is a perspective view of a modified wall construction;

Fig. 14 is a section view of an alternative detail of wall construction;

Fig. 15 is a similar view of another embodiment;

Fig. 16 is a broken sectional view of a house;

Fig. 17 is a perspective detail view;

Fig. 18 is a section of a roof and girt assembly; and

Fig. 19 is a perspective view of a portion of a floor.

In its preferred embodiment the invention comprises standardized units of the type illustrated more particularly in Figs. 1 and 2, which preferably have a length corresponding to some dimension of a room or bay, such as the height of a story or the width or length of a room. Such a unit consists of a tubular body portion 1 having a flat surfaced outer wall 2; it being understood that the term "tubular" body portions is applied to an elongate hollow member of any cross-sectional form, whether, for example, cylindrical, rectangular or trapezoidal, as illustrated in the various embodiments of the invention or otherwise. The hollowed body of the member 1 may be formed upon three sides by the sheet member 3 which has the inclined

95

105

110

walls 4 and 5 connected by the wall 6 parallel to the flat surface 2. The flat surface 2 is preferably formed by a face of plank 7, which may consist of fibrous or light cementitious material, while the sheet 3 is preferably of metal, although various other suitable materials may be used for either of these members. Any suitable fastening means such as screws may be used to secure the members 10 3 and 7 together, while the nailing strip 8 of wood or other fibrous material may be similarly secured upon the face 6 of the metal sheet 3.

The above described unit obviously may be 15 combined with other like units in many various manners as suggested in this or in my co-pending applications, one installation being illustrated in Fig. 2 which shows a floor built up of a series of these units, the surfaces 20 2 of planks 7 forming a continuous finish for the ceiling of a lower story and the spaces between the metal portions 3 being filled with concrete or cementitious material 9, while the upper faces of the wooden strips 8 are left 25 uncovered to provide nailing surfaces for the application of floor boards 10 or the like. Obviously, these units may be combined in a similar manner to form walls or roofs with the strips 8 constituting means for the attachment 30 of laths, wall-board, metal sheathing or other material. The wooden planks 7 may either form the finish of a wall or of a roof of a building or these members may constitute a suitable surface for the application of 35 finishing material.

Fig. 3 illustrates a slightly different embodiment of my invention wherein the body portion of the tubular unit 10 has inclined walls 4 and 5 as in Fig. 1, but the walls 4, 5 40 and 6 are separate pieces or slabs which may be formed of any suitable material such as wood or other fibrous material, or of light cementitious material such as gypsum, or of fibrous or granular material combined with a 45 cementitious binder. These units likewise may be combined in roofs, walls, or floors, the planks 7 thereof providing continuous 50 surfaces in the manner that has been described, while the slabs 6 may form spaced aligned surfaces for the attachment of roofing material, wall finish, floor-boards or the like.

Figs. 4, 5 and 6 show other forms of structural units having similar characteristics 55 and which may be formed of a similar material, but which are distinguished by the fact that the tubular portion has substantially rectilinear walls. The embodiment shown in Figs. 5 and 6 also has equally dimensioned 60 continuous surfaces 13 and 14 extending upon either side thereof. Obviously these units may be combined in various relations in the manner that has been described above. The flanged surfaces 13 and 14 of the unit shown 65 in Fig. 5 are particularly adapted to hold

the units in accurate alignment as illustrated by Fig. 6, in which these units are shown as assembled to form a wall, with a layer of stucco 15 applied to the surfaces 13, while the surfaces 14 form the finish for the other 70 side of the wall.

Fig. 7 illustrates another embodiment of my invention of a shape similar to that shown in Fig. 6 but being more particularly adapted to be constructed of fiber board or 75 the like, although it may be made of wood or any other suitable material. The binding 18 within the hollow body portion is of light cementitious material, such as gypsum, and serves to bind the walls of this unit together 80 without the necessity of depending wholly upon nails, or similar securing means, to penetrate the fiber board or the like. This construction is especially advantageous with a substance which is not adapted to hold nails 85 or screws firmly.

Fig. 8 shows another form of unit constructed in accordance with my invention 90 and having a curved tubular body portion 19, which may be cylindrical in form, with a flat surfaced portion 20 at one side thereof. Obviously such a unit is more particularly adapted to floor or roof construction and may be combined with like units to form a structure quite similar to that illustrated in 95 Fig. 2. Such a unit may be formed of metal and wood, of various fibrous materials, of cementitious material, or of fibrous or granular material combined with a cementitious binder, or of various combinations of such 100 materials.

Fig. 9 shows a unit formed of a cementitious material such as gypsum, or of any suitable material such as those previously described, and which has continuous flat surfaces 21 upon either side and is provided with integral flanges having flat surfaces 22 at the outer ends thereof. These surfaces 22 are of a suitable size to provide an abutting area for firmly holding the unit in proper 110 juxtaposition with similar surfaces of adjoining units.

Fig. 10 shows a unit quite similar to that of Fig. 3 but formed of metal or similar sheet material and a slab of cementitious or fibrous material, the inclined walls 5 and 6 of this unit joining in a curved portion to reinforce the sheet portion of the unit. This unit may be combined with like or similar units in many relations in the manner described in this and my co-pending applications and is more particularly adapted to use where it is not desired to apply sheets or strips of finishing material to one side of the units as for example in a floor or roof having 125 an upper layer of concrete.

In constructing a building from any of the various types of units described above, many different means of combining the units may be used as suggested in my co-pending appli- 130

cations, or as shown in Figs. 16, 17 and 19, wherein a foundation 42 is formed with an outer portion 43 having its upper surface substantially above that of the inner portion 5 to form a recess 44. Standardized units 41 which may be any of the types previously described, such as those shown in Fig. 5 for example, are then laid with their end upon the foundation in order to form a basis for the lower floor of the building. Blocks 45 secured in a spaced row by a pair of metallic straps 46, or the like, (Fig. 17) are disposed in the ends of the tubular body portions of units 41, cementitious material being poured in the recess 44, forms a girt or sill 52 with monolithic portions extending into the tubular recesses formed by the flanges between the body portions of adjoining units 41.

Disposed upon the top of girt 52 and portion 53 of the foundation are the Z-shaped flash strip 57 and straps 56 similar to straps 46 and secured to a series of blocks 45 in a like manner. The blocks 45 engage the lower ends of vertical wall units 41, which may 25 be similar to the floor units 1 but have their outer walls extended upwardly as indicated at 55. Disposed in the upper ends of the wall units 41 are blocks 65, which are secured to extension 66 of the lower surfaces of units 30 41^b, which define the floor for the second story. These extensions 66 may be of the full width of the units, or they may be restricted in width, as shown, in order to permit the pouring of cementitious material between 35 the tubular body portions of wall units 41, or if desired, the extension 66 may be entirely omitted upon certain floor units to allow the filling of the corresponding wall units with cementitious material. Concrete, or the 40 like, may then be poured over the ends of the wall units to provide a girt member 60 having monolithic portions 59 extending into the recesses formed by flanges 51 of adjoining units 41^b and also between the wall units if desired. 45 Any desired number of stories may be erected in a similar manner.

It is evident that stucco 15, such as illustrated in Fig. 6, may be applied to one or both of the surfaces of the wall units, certain spaces 50 between or within which are filled with cementitious materials or concrete. Thus a wall is provided which is formed of upright rough-surfaced boards of cellular material united at intervals and having concrete poured therebetween and stucco applied to exposed surfaces thereof.

In order to construct a pitched roof of the form illustrated in Fig. 16, units 41^c, similar in general form to those previously described, 55 may be disposed in an inclined position to form the basis for such a roof with a series of blocks 45 inserted in their upper ends and individual blocks 61 fitted in their lower ends as shown. The outer surface 63 of these 60 units are extended and form an overhanging

portion of the pitched roof. The lower ends of the unit 41^c may have their side walls notched to engage with key beams 70 extending along the margin of the upper floor 68, while the upper ends of the units rest upon 70 the ridge member 69. Concrete may then be disposed between the upper ends of the units above member 69 to provide a concrete ridge 67 having lateral extensions lying between the body portion of units 41^c and joining it 75 with a girt member 78 formed above the ends of the wall units. If desired all, or certain of these members may be formed in one operation to constitute a monolithic structure. An attractive optional arrangement may be 80 obtained by the use of a rather wide ridge member 69, resulting in the provision of a flat concrete ridge.

Fig. 18 illustrates the provision of a girt 85 83, when the lower portion of a pitched roof is not adjacent a floor as described above. With this type of construction blocks 45, engaged in the upper ends of wall units 41, blocks 61 in the units 41^c, together with the extensions of the outer sides of the wall units 90 and of the units 41^c, serve to constitute a form for the pouring of girt 83, which may be connected by monolithic extensions with the ridge in the manner previously described.

While I have shown and described the incorporation of one type of standardized unit in a building construction, it may readily be seen that many other types of units may be combined in a similar manner by a suitable mechanical re-arrangement of parts, such as the 100 reshaping of the blocks 45 or the disposing of concrete about the units in an appropriate manner.

Fig. 11 illustrates an alternative mode of 105 wall or roof construction which may be adopted with any of the forms of structural units described in this application, but for purposes of convenient illustration, units such as shown in Fig. 5 are shown in Fig. 11. The flat surfaces of these units are beveled 110 at their longitudinal edges as at 31. The beveled surfaces 31 may form an attractive variation in finish as in the case of panels 14, while upon the side of a wall forming the outer side or roof of a building, suitable 115 means may be applied to afford additional weather protection. As shown in Figs. 11 and 12, tar paper 37 or the like may be applied to the inner surfaces of adjoining flanges while metal flash strips 34 may be 120 secured to the beveled surfaces 31 in any suitable manner as by nails 35. Preferably these strips have a flat outer face with inclined surfaces at either side which have edges abutting the beveled portions 31 of 125 adjoining slabs or panels.

Another method of providing flash strips is shown in Fig. 14, wherein there is a flat strip 38 having a mastic substance 32 interposed between it and the beveled surfaces. 120

Fig. 13 illustrates a modified design, wherein marginal flanges 36 are formed upon the faces 13 of the unit illustrated in Fig. 6. Such a flange has an outer surface substantially aligned with a similar surface upon an adjoining unit, the two flanges being covered by a metal strip 39 having its margins secured, as by brads 40, to the flanges 36 of adjoining units.

- 10 An alternative mode of finishing outer walls and roofs is shown in Fig. 15, wherein the joint between flat walls of adjacent units is sealed by a member 83 which is of substantially I-shape in cross section, with flanges 84 and 85 overlapping the inner and outer marginal surfaces respectively of the adjoining walls of structural units. Such a strip is preferably formed of sheet metal as shown, although other modes of construction may be used. Upon assembly a member 83 has one side fitted to the edge of the wall of a unit and then the edge of the adjoining unit is engaged with the other side of the strip. Many other ways of joining the flat surfaces of the units may be devised in accordance with constructions in analogous locations, for example adjoining flange portions may be rabbeted to overlap each other or many equivalent expedients may be used.
- 15 Not only may the above described units be made of a wide variety of materials, but obviously they may be combined with each other and the units described in my copend-

ing applications in many different ways to suit individual conditions. Certain units may be more adaptable to wall construction and others preferable for floors or roofs. Cement or concrete may or may not be interposed in various spaces within or between certain units. Finishing material may or may not be applied to their outer surfaces. The units may be set in a continuous depression to form walls in the manner described in copending applications Nos. 72,673, 72,674 or key members, such as described in application No. 72,678 may be used to tie the units to the adjoining structure. Members designed to engage the inner surfaces of the ends of tubular portions may also be constructed after the manner described in copending applications No. 33,173 or No. 72,678 filed of even date herewith. These and various other modifications and expedients may be adopted in utilizing my invention in practical construction.

I claim:

A building wall comprising outer and inner upright rough-surfaced boards of cellular material united at intervals and having concrete between the opposing surfaces of the boards, the exposed surfaces of the outer boards having a stucco finish directly applied thereto.

Signed by me at Boston, Massachusetts, this 30th day of October, 1925.

ALBERT F. BEMIS.
